Specification for Design.

Patented Dec. 10, 1912.

Application filed October 2, 1912. Serial No. 723,647. Term of patent 7 years.

To all whom it may concern:

Be it known that I, CHARLES E. GRELLE, a citizen of the United States, and a resident of the city of Portland, county of Multnomah, and State of Oregon, have invented a new, original, and ornamental Design for a Lamp-Post, of which the following is a specification, reference being had to the accompanying drawing, forming part thereof.

The figure of the drawing is an elevation of a lamp-post, showing my new design.

I claim:

The ornamental design for a lamp-post, as shown.

CHARLES E. GRELLE.
